United States Patent Office

Des. 184,469
Patented Feb. 17, 1959

184,469

PORTRABLE FAN

Henry Zeiler and Albert H. Herter, Denver, Colo.

Application May 2, 1957, Serial No. 45,993

Term of patent 14 years

(Cl. D26—7)

FIG. 1

Fig. 1 is a front view of a portable fan showing my new design, and

Fig. 2 is a side view thereof.

The rear of the portable fan has the same appearance as the front view of Fig. 1, and the opposite side thereof has the same appearance as the side shown in Fig. 2.

We claim:

The ornamental design for a portable fan, as shown and described.
